UNITED STATES PATENT OFFICE.

CHARLES F. SPENCER, OF ROCHESTER, NEW YORK.

HOSE-CO尤PLING.

Specification of Letters Patent No. 30,261, dated October 2, 1860.

To all whom it may concern:

Be it known that I, CHARLES F. SPENCER, of Rochester, in the county of Monroe and State of New York, have invented a new and 5 Improved Coupling for Connecting Hose and other Pipes; and I do hereby declare that the following is a full and exact description thereof, reference being had to the accompanying drawings, making part of 10 this specification.

Figure 1, is a longitudinal section of my coupling. Fig. 2, is a transverse section on the line x x of Fig. 1. Fig. 3, is a transverse section on the line y y of Fig. 1. Fig. 4, is 15 an elevation of the entering section B, detached.

Like letters designate corresponding parts in all of the figures.

The object of my invention is the production of a coupling which may be instantly connected or disconnected, and which shall be self-packing whenever it is in use, without the aid of screws, cams or wrenches.

As represented in the drawings A, B, are 25 the two sections of the coupling, to each of which the hose C, C, is attached. These parts consist of two metallic tubes having a bore of a diameter nearly corresponding with that of the hose to which they are attached.

30 B is the entering, and A, the receiving section; the latter being bored out of a large size to allow the former to enter till the shoulder e strikes the end of A. At a point corresponding with the end of B, when inserted, an annular chamber d is formed in the interior of A, of a depth from $\frac{1}{4}$ to $\frac{1}{2}$ inch, varying with the diameter of the pipe. In this chamber a flat ring of packing f is inserted, having an opening corresponding 40 with the bore of the pipe. Its external diameter should be slightly less than that of the chamber d so as to allow it to move freely therein. This packing may be composed of india-rubber, leather or other packing material having sufficient flexibility and elasticity for the purpose, and which will withstand the action of water.

When the two parts of the coupling are connected, the packing ring f is free to move 50 in the recess d until water is passed through the hose, in the direction of the arrow, when the force thereof impacts the ring f on the end of the post B, and shoulder of the chamber d , completely closing the joint between

the two. The greater the force of the water 55 the more perfect the packing is upon the joint, and it cannot yield so long as the water continues to flow in that direction. In attaching the parts of the coupling to the hose it should be borne in mind that A is 60 attached to the hydrant portion, and B, to the nozzle section, or in the same relative positions however many sections of hose there may be.

The fastening which keeps the parts A, 65 and B, from separating is a spring latch or catch g Figs. 1, and 3, which is pivoted at one end in a slot which lies transversely of the part A. The inner edge of this projects an eighth of an inch or thereabout from the 70 interior surface of A, and falls into a groove i in the part B, as soon as that part is fully inserted. This groove extends quite around the section B, and allows it to turn freely in A, without disconnecting the two. This is 75 an important feature, as it frequently occurs that the hose becomes twisted, an accident which cannot be remedied with the ordinary coupling without uncoupling, which is difficult, and sometimes impossible to perform 80 without stopping the flow of water. This device forms a swivel joint by which the parts will turn together in either direction without making the connection insecure, and the packing of the joint remains perfectly 85 tight the meanwhile. Indeed so easily does the joint turn, that the slight rigidity of the hose is sufficient for that purpose whenever a twist occurs, so that the effect is to prevent 90 that occurrence.

The latch is provided with a spring m under its heel, which may be made of india rubber, or of metal, applied in any manner that will have the effect to hold it down until it is raised for the purpose of uncoupling the parts. The end of B, is made slightly conical and the outer edge of the latch is rounded or beveled so that the insertion of B, into A raises the latch, which the spring causes to fall into the groove. 100 Thus the work of connecting and fastening is instantly effected by merely placing the two parts together, which can be done without difficulty while the water is flowing.

I do not confine myself to the particular 105 form of latch represented, as any other kind which has the power to self-connect and to permit one section of the coupling to turn

independently of the other will answer equally well.

What I claim as my invention, and desire to secure by Letters Patent, is—

5 1. My improved packing for hose couplings, consisting of the loose ring *f* of india rubber, or its equivalent, in combination with the annular chamber *d* for retaining the same in a position to readily impact with
10 the end of the inserted section, *B*, by the

force of the water passing through the hose, substantially as set forth.

2. In combination with said packing ring, the groove *i* on the neck of tube *B*, and latch *g* or its equivalent, substantially as and for 15 the purposes specified.

CHAS. F. SPENCER.
